UNITED STATES PATENT OFFICE

150,278

DESIGN FOR A JACKET OR THE LIKE

Satrauna W. White, Seattle, Wash., now by decree of Marriage Satrauna W. Luckett

Application April 15, 1946, Serial No. 128,621

Term of patent 14 years

(Cl. D3—4)

To all whom it may concern:

Be it known that I, Satrauna W. White, a citizen of the United States of America, residing at Seattle, in the county of King and State of Washington, have invented a new, original, and ornamental Design for a Jacket or the like, of which the following is a specification, reference being had to the accompanying drawing, forming part thereof.

The back portion of the jacket, the inside portion of each sleeve, the exposed portion of the collar, and the marginal portion of the several buttons are lined to represent a dark color, whereas the other portions of the jacket exterior, as shown, would be light in color.

I claim:

The ornamental design for a jacket or the like, as shown and described.

SATRAUNA W. WHITE,
Now by Decree of Marriage Satrauna W.
Luckett.
